UNITED STATES PATENT OFFICE.

JESUS M. LÓPEZ, OF SAN ANTONIO, TEXAS.

TIMER.

Application filed May 5, 1922. Serial No. 558,822.

To all whom it may concern:

Be it known that I, JESUS M. LÓPEZ, a citizen of Mexico, residing at San Antonio, in the county of Bexar and State of Texas, have invented new and useful Timers, of which the following is a specification.

One object of this invention is to provide novel means whereby a reduction of speed between the cam shaft of an engine and a timer arm is effected, wear on the contact elements being reduced accordingly. Another object of the invention is to provide novel means whereby the casing of the timer may be adapted to receive the oil which is discharged into the crank case of the engine, the timer being lubricated by the oily fumes proceeding from the crank case. Another object of the invention is to improve the track and the terminals which are traversed by the roller on the timer arm.

With the above and other objects in view which will appear as the description proceeds, the invention resides in the combination and arrangement of parts and in the details of construction hereinafter described and claimed; it being understood that, within the scope of what is claimed, changes in the precise embodiment of the invention shown can be made without departing from the spirit of the invention.

In the drawings:—Figure 1 shows in elevation, a device constructed in accordance with the invention; Figure 2 is a section on the line 2—2 of Figure 1; Figure 3 is a top plan; Figure 4 is a section on the line 4—4 of Figure 2; Figure 5 is a section on the line 5—5 of Figure 2; Figure 6 is a section on the line 6—6 of Figure 2.

The device comprises a support including a pedestal 1 having a foot 2 provided with extensions 3 for securing the device in place on an engine, a cap 4 being held in one end of the foot 2 by any suitable means. A thrust bearing 25 is threaded into the lower end of the foot 2. The support includes a head 6 comprising a cup-shaped base 7 having a funnel-shaped bottom 8 carrying a sleeve 9 receiving the upper end of the pedestal 1, the bottom having a tubular outlet 10, a screen 11 being held in the base 7 above the outlet. The base 7 carries an arm 12 which aids in supporting the device. At its upper end, the base 7 is circumscribed by an offset annular flange 14.

The head 6 includes a tubular upper member 15 surrounding the base 7 and seated

removably in the flange 14, the parts 7 and 15 having ears 16 whereunto the ends of retractile springs 17 are connected detachably, the springs serving to hold the member 15 on the base 7. A bracket 18 projects from the upper member 15 and aids in supporting the structure. The member 15 is provided adjacent to its upper end with an inwardly projecting annular rib 19. A lid 20 is hinged at 21 to the member 15 of the head 6 and has a latch 22 adapted to cooperate with a keeper 23 on the part 15. The member 15 has side openings 24.

The cam shaft 26 of an internal combustion engine projects into the foot 2 of the pedestal 1, a worm 27 being located in the foot, and being keyed at 28 to the cam shaft 26. A timer shaft 29 is journaled in the pedestal 1 and has a collar 32 engaging the foot 2, the lower end of the shaft being received in the thrust bearing 25, the parts 25 and 32 cooperating to prevent the shaft 29 from moving endwise. A pinion 30 is keyed at 31 to the timer shaft 29 and is located in the foot 2, the pinion meshing with the worm 27 on the cam shaft 26.

An insulating ring 33 is located within the member 15 and rests on the upper end of the base 7, the ring being L-shaped in cross section. An annular track 34, of insulating material, is supported on the ring 33, the track supporting an intermediate insulating ring 35, which is T-shaped in cross section, the ring 35 carrying an annular insulating track 36 supporting an insulating ring 37, which is L-shaped in cross section, the ring 37 being received beneath the rib 19 on the member 15, all of the rings and tracks being bound between the upper edge of the base 7 and the rib 19. An annular conducting member 38 is located between the ring 37 and the track 36 and is insulated by the ring 37 from the part 15. The conducting member 38 has depending terminals 39 seated in notches in the inner edge of the track 36. An annular conducting member 40 is disposed between the track 36 and the ring 35 and is spaced by the ring 35 from the member 15 of the head 6. The conducting member 40 has upstanding terminals 41 which are seated in notches in the inner edge of the track 36. An annular conducting member 42 is disposed between the ring 35 and the track 34 and has depending terminals 43 seated in notches in the inner edge of the track 34. An annular conducting member

- 44 is located between the track 34 and the ring 33 and has upstanding terminals 45 seated in notches in the inner edge of the track 34. The conducting members 38, 40, 5 42 and 44 are provided with outwardly extended binding posts 47 passing through insulating plates 48 received in the openings 24 of the member 15 and extended downwardly behind the flange 14 on the base 7.
- 10 A nut 49 is threaded on the upper end of the timer shaft 29 and retains thereon a collar 50 having an outstanding finger 51. The device comprises a lever including an arm 53 having a socket 54 connected by pivot 15 elements 55 with projections 56 extending from the collar 50, the numeral 57 marking a fork provided with a stem 58 held in the socket 54 of the lever, a roller contact 59 being journaled at 60 on the fork 57,
- 20 the roller being adapted to traverse the tracks 34 and 36, and to engage with the contacts, or terminals, such as the elements 45, for instance. One end of a retractile spring 61 is connected to the finger 51 on 25 the shaft 29, the other end of the spring being connected to the arm 53 of the lever. The spring 61 maintains the roller 59 yieldingly in engagement with the tracks 34 and 36.
- 30 Especial attention is directed to the fact that, owing to the provision of the worm 27 on the cam shaft 26 and the pinion 30 on the timer shaft 29, the timer shaft rotates much more slowly than does the cam shaft. Likewise, the roller contact 59 moves with comparative slowness over the tracks 36 and 34, wear on the tracks being avoided accordingly. Any desired speed reduction may be brought about between the cam shaft 26 40 and the timer shaft 29, the number of conducting members 40, 42, 44 and 38 being determined accordingly, each contact member having as many or as few of the terminals, such as the part 45, as may be expedient.
- 45 The oil may be introduced into the crank case of the engine through the head 6 and the outlet 10. The oily fumes, proceeding from the crank case, will enter the head 6 through the part 10 and will bring about a 50 lubrication of those parts of the timer which are located within the head 6. If desired, a channel 100 may be formed in the upper end of the pedestal 1, the channel being adapted to hold a quantity of oil which will flow slowly into the pedestal, lubricating the shaft 29, the worm 27 and the pinion 30.
- I claim:
1. In a device of the class described, a head comprising telescoped parts, a track within the head and bound between the parts 60 of the head, spring means for connecting the parts of the head to cause them to hold the track, and a timer movable in the head and cooperating with the track.
  2. In a device of the class described, a head, a track in the head and having seats in its inner edge, an insulating ring disposed approximately parallel to the track, an annular conducting member located between the ring and the track and having 70 angular terminals received in the seats of the track, the insulating ring comprising a flange located between the conducting member and the head, and timing mechanism cooperating with the track.
  3. In a device of the class described, a support comprising a pedestal and a cup-shaped head assembled with the pedestal, a shaft journaled in the pedestal, a track in the head, and a contact element carried by 80 the shaft and cooperating with the track, the head being provided with means independent of the pedestal for receiving oily vapor from the crank case of an internal combustion engine and for conducting the 85 oily vapor to the head, said means being so constructed as to transfer liquid oil from the head to the crank case of an internal combustion engine, the track being of annular form to facilitate the pouring of liquid oil into said means and into the bottom of the head.

In testimony that I claim the foregoing as my own, I have hereto affixed my signature in the presence of two witnesses.

JESUS M. LOPEZ.

Witnesses:

C. M. DICKSON,
MAURINE TOWNSEND.
